UNITED STATES PATENT OFFICE.

HENRY U. PRINDLE, OF WOODLAND, CALIFORNIA, ASSIGNOR OF ONE-HALF
TO JOHN W. GUTHRIE, OF SACRAMENTO, CALIFORNIA.

SASH-LOCK.

SPECIFICATION forming part of Letters Patent No. 645,213, dated March 13, 1900.

Application filed March 29, 1899. Serial No. 711,041. (No model.)

To all whom it may concern:

Be it known that I, HENRY U. PRINDLE, residing at Woodland, in the county of Yolo and State of California, have invented a new and 5 Improved Sash-Lock, of which the following is a specification.

This invention, which relates to improvements in sash-locks, more particularly refers to that class of sash-holders in which the lock 10 is mounted in the window-casing and provided with suitable clamping means for engaging the sash and holding it locked to any of its adjusted positions.

Primarily my invention seeks to provide a 15 lock device of this character of a very simple and economical nature, which can be easily fitted to the window casing and sash, easily manipulated, and which will effectively serve for its intended purposes.

20 This invention comprehends a novel construction of sash-lock having a combined guide and lock member movable with the sash and lock-clamp devices held to engage such member when under a normal condition 25 and to be moved to a position to allow for a free play of the said combined lock and guide member when they (the clamp devices) are manipulated by the unlocking key or tumbler.

30 In its subordinate features my invention embodies a peculiar combination of parts and novel details of construction, as will be first described in detail and then be specifically pointed out in the appended claim, reference 35 being had to the accompanying drawings, in which—

Figure 1 is a face view of a portion of a window with my improved sash-lock device applied. Fig. 2 is a vertical section of a portion of the window sash and casing and my improved locking devices, the lock-clamps being shown to their normal (locked) position in full lines and to their unlocked position in dotted lines. Fig. 3 is a horizontal 40 section of the parts shown in Fig. 2, taken on the line 3 3. Fig. 4 is a transverse section on the line 4 4, illustrating the key or tumbler devices more clearly. Fig. 5 is a detail view of the tumbler. Fig. 6 is a detail 45 view of one of the sash-brackets or bearing members for the slide-rod. Fig. 7 is a detail

view of the lock-casing and detachable cover-plate therefor, and Fig. 8 is a detail view of one of the pivoted clamp-plates hereinafter particularly referred to.

55

In the practical construction my improved sash-lock comprises a casing the major portion of which has the several parts integrally formed and comprising a back plate 1 and top and bottom plates 2 3, provided with bosses 60 2^a 3^a, having threaded sockets for the screws which secure the detachable cover-plate 4 in place, said top and bottom plates also having vertical face portions 2^b 2^c, which form the securing-flanges which are apertured for 65 the passage of the securing-screws 5 5. The casing is also formed with an integral front side portion 6, which merges with the loop or sheath 7, disposed over the front face of the lock-casing, but which is of a length less 70 than the height of the front open end 8 of the casing, whereby open ways 9 9^a are formed at the upper and long ends of such front for a purpose presently explained. The front and back walls of the casing have alin- 75 apertures 11 11^a to receive the ends of the hub 12^a of the tumbler 12, the construction of which is clearly shown in Figs. 2 and 5, by reference to which it will be seen the hub has a non-circular transverse aperture 13, adapted 80 to receive the flattened end 14^a of the operating-key shank, which has a finger-knob 14, preferably formed integrally therewith and having an annular groove 14^b to receive the inner semicircular edge of the divided washer- 85 plate 15, which is secured to the casing and serves as a retainer to hold the key-shank in its proper position, as clearly shown in Figs. 1 and 4.

90 In the practical application of my invention mortises are cut in the runways of the sash, one near the upper end of the lower sash and the other near the lower end of the upper sash, into which the lock-casings, with their integral members, are fitted, their secur- 95 ing-flanges 2^b 2^c being fitted in countersunk depressions to bring their faces flush with the slide-face of the runways, and with each lock-casing mortise connects the key slot or bore 16 16, as clearly illustrated in Fig. 4, by 100 reference to which and to Fig. 1 it will be observed that nothing of my sash-lock devices

but the finger-knob and the retainer-washer appear to view. The front back-walls of the lock-casing near their upper ends have coincident apertures 17, which form bearings 5 for their laterally-projected pintles 18^a on the swinging clamp-plates 18, (in practice made of steel,) which have their front ends projecting through the open ways 9 9^a and in line with the sheath or loop portion 7, while 10 their inner ends rest against the opposite sides of the tumbler, against which they are always held pressed by the stout coil-spring 19, disposed about the slide-rod 20 and between the outer ends of such clamp-plates 18, 15 which ends are provided with apertures 21, slightly elongated for a purpose presently described and through which the slide-rod 20 passes.

The slide-rod 20 is secured to and travels 20 with the sash 22, and to provide for a simple means of adjustment said rod has its opposite ends formed with right and left threads adapted to engage with the correspondingly-apertured bracket-plates 24, secured in countersunk seats to the upper and lower edges of the sash, the lower end of the rod 20 terminating on the slotted hub, whereby it may be readily turned by means of a screw-driver.

As will be seen by reference to Figs. 2 and 30 3, the rod 20 is held flush with the outer edge of the sash, which is provided with a longitudinal groove to receive it, which groove, however, is of a width sufficient to allow for a free sliding of the sash edge over the loop 35 or sheath 7 of the lock-casing, which encircles the said rod 20.

From the foregoing, taken in connection with the drawings, it is thought the operation and advantages of this invention will be readily understood. It will be seen by arranging 40 the clamp mechanism as described and shown the normal action thereof will be to clamp the rod 20 and hold the sash from movement in either direction, and by turning the key to the 45 right the tumbler will swing the clamp-sash so that the front ends will close toward each other sufficient to release their clamping action and bring their apertures in such relation to the sash 22 as to admit of its sliding 50 freely therein, the apertures of the said clamp members being slightly elongated for this purpose, it being understood that when thus shifted to the right the tension of the spring

will cause the inner ends of the clamps to bear 55 tightly against the tumbler, and thereby maintain the said clamps in their unlocked position until such tumbler is again shifted to the left.

By arranging the spring on the rod 20 the same can be quickly fitted in place and at all 60 times held in a position in which it cannot be readily broken or dislodged. Furthermore, by constructing the easing in the manner shown and arranging the clamps as described the lock can be manufactured at a very low 65 cost and be of a strong and durable character. Again, by providing the casing with an integral loop or sheath member 7 the rod 20 will at all times be held to its proper alignment and the spring from frictional contact 70 with any part of the sash, the sheath also forming a long guide-bearing for engaging the sash to overcome any sagging or rattling thereof.

While I have shown my improvements as 75 more especially adapted as a sash-locking means, it is manifestly not confined to such use only, as it can be employed in various mechanical devices where it is desired to hold a sliding member locked to any of its adjusted 80 positions.

Having thus described my invention, what I claim, and desire to secure by Letters Patent, is—

In a sash-lock of the character described; 85 the combination with the sash having a grooved edge and the vertically-disposed slide-rod secured thereto; the lock-casing having an open front edge and an integrally-formed sheath or loop projected over said front edge, 90 and adapted to engage the sash-groove and form a fixedly-held guide for the sash and to hold the same from engagement with the clamp device; a pair of opposing clamp members pivotally mounted within the casing—a 95 tumbler means for adjusting the clamps to a released position, said clamps having elongated apertures for the slide-rod, and a coiled spring held about the rod between the apertured ends of the clamps, all being arranged 100 substantially as shown and for the purposes described.

H. U. PRINDLE.
